SWITCH

Filed April 22, 1929

UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF DELAWARE

SWITCH

Application filed April 22, 1929. Serial No. 357,118.

This invention relates to improvements in switches and refers more particularly to key controlled ignition switches and the like and has as one of its objects to provide a switch ⁶ of the character described which is exceptionally compact.

Another object of this invention resides in the provision of a switch of the character described in which the cylinder mounting ¹⁰ head forms a housing in which the switch elements are confined.

Another object of this invention resides in the provision of a switch of the character described in which the movable contactor is actuated directly from the inner end of the ¹⁵ lock cylinder.

And a further object of this invention is the provision of a switch of the character described which when assembled with its ²⁰ lock structure is a simple unitary device entirely contained within itself.

With the above and other objects in view which will appear as the description proceeds, my invention resides in the novel construction, combination and arrangement of parts substantially as hereinafter described and more particularly defined by the appended ²⁵ claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a transverse, sectional view with parts in elevation taken through a ⁴⁰ switch embodying my invention;

Figure 2 is a cross sectional view taken through Figure 1 on the plane of the line 2-2;

Figure 3 is a fragmentary, perspective view of the inner end of the lock structure with the switch elements removed therefrom;

Figure 4 is a perspective view of the movable contactor, its drive member, the spring, and the insulated spring seat shown dis- ⁵⁰ assembled, and

Figure 5 is a perspective view of the terminal head.

Referring now more particularly to the accompanying drawings in which like numerals designate like parts throughout the ⁵⁵ several views, the numeral 5 represents the mounting head or body of a conventional lock structure, which forms the mounting means for the switch elements, as will be later described, and in whose bore 6 a lock cylinder 7 is rotatably mounted. The lock cylinder ⁶⁰ 7 is held against longitudinal movement at its inner end by a shoulder 8 formed at the juncture between the bore 6 and a second smaller bore 9, and at its outer end by a cap member 10 formed of bendable metal shaped to the contour of the outer end of the mounting head and spun over an annular projection ⁶⁵ 11 extended therefrom, as is customary.

The lock cylinder 7 is provided with the ⁷⁰ usual tumblers 12 which cooperate with longitudinal grooves 13 in the mounting head to secure the cylinder against rotation except when a proper key 14 is inserted in the cylinder, whereupon the tumblers are retracted ⁷⁵ within the cylinder, which is then free to be turned.

The switch per se includes a terminal head ⁸⁰ 15 carrying terminals 16 and 17 with which suitable conductors may be connected, and which are secured to the terminal head 15 by rivets 18 and 19, the heads of which are embedded in the inner face of the terminal head and form the stationary contacts of the switch. A movable contactor 20 stamped from bendable metal, as best illustrated in Figure 4, is adapted to be engaged with the stationary ⁸⁵ contacts to electrically bridge the same when the lock cylinder is turned to its unlocked position. The movable contactor is of sub-

stantially elongated, diamond shape and has flanges 21 extended laterally from its sides which are received in a similarly shaped aperture 22 in a drive member 23. ⁹⁰

The drive member 23 comprises a disc of ⁹⁵ insulating material, such as fiber or the like, and is received within a counterbore 24 extended into the inner end of the lock structure mounting head outwardly of the bore 9, being rotatable therein with the cylinder. ¹⁰⁰

Rotation of the cylinder 7 is imparted to the drive member 23 by ears 25 extended from spaced lugs 26 projected from the inner end of the lock cylinder, and received in diametrically opposed notches 27 formed in the drive member outer periphery, the drive member resting on the outer faces of the lugs 26.

Displacement of the drive member is prevented by the terminal head 15 which is secured on the inner end of the mounting head 5 by spaced projections 28 extended therefrom and spun over the outer face of the terminal head, the periphery of the terminal head being reduced in diameter, as at 29, to receive the projections 28.

As best illustrated in Figure 4, the ends 30 of the movable contactor are in a plane spaced outward of the medial portion so that when moved to "off" position, as illustrated in dotted lines in Figure 2, the medial portion thereof will be clear of the stationary contacts. Proper contact between the ends 30 of the movable contactor and the stationary contacts is obtained from the action of an expansive spring 31, received between the flanges 21 of the movable contactor and confined between the movable contactor and a spring seat 32 formed of insulating material and received within a recess 33 formed in the adjacent inner end of the lock cylinder 7.

From the foregoing description, taken in connection with the accompanying drawing, it will be readily apparent to those skilled in the art to which an invention of the character described appertains, that I have provided a convenient and extremely compact switch which may be securely locked against actuation, and which may be utilized for numerous purposes and by reason of its extreme compactness and relatively small size lends itself readily for use wherever compactness is a prerequisite. To facilitate its securement to a support, a portion of the mounting head 5 is exteriorly threaded to receive a nut 34, the support, which usually consists of a panel or the like, thus may be impinged between the annular projection 11 and the nut 34.

What I claim as my invention is:

1. A lock switch of the character described, including a mounting head provided with a first bore adapted to receive a lock cylinder, a second bore adapted to receive a switch mechanism, a third bore of smaller diameter than said first named bore and connecting said first and second named bore, a lock cylinder mounted within said first named bore abutting the shoulder formed between said first and said third named bores, a switch head on the outer end of said second named bore, a plurality of contacts on said switch head, a contactor actuating member mounted for rotation within said second named bore, a pair of arms formed on said lock cylinder and engaging said contactor actuating member to effect rotation thereof, a contactor carried by

said actuating member and adapted to selectively engage or disengage said points upon rotation of said actuating member.

2. In a lock switch of the character described, a mounting head provided with a first bore adapted to accommodate a mounting cylinder, a second bore adapted to accommodate a switch mechanism and a third bore joining said other two bores and of smaller diameter than said first named bore, a lock cylinder mounted in said first named bore for rotation therein and abutting the shoulder formed between said first and third named bores, a switch head mounted at the outer end of said second named bore, a plurality of switch points mounted on said switch head, a contactor actuating member mounted for rotation within said second named bore, a pair of arms formed on said lock cylinder and engageable with said last named member to effect rotation thereof, a contactor mounted within said contactor actuating member and adapted to selectively engage or disengage said points upon rotation of said actuating member and means constantly urging said contactor into engagement with said switch head.

3. In a lock switch of the character described, a mounting head provided with a first named bore adapted to accommodate a mounting cylinder, a second named bore adapted to accommodate a switch mechanism and a third named bore joining said other two bores and of smaller diameter than said first named bore, a lock cylinder mounted in said first named bore for rotation therein and abutting the shoulder formed between said first and said third named bores, a switch head mounted at the outer end of said second named bore, a plurality of switch points mounted on said switch head, a contactor actuating member mounted for rotation within said second named bore, a plurality of arms formed on said lock cylinder and engageable with said contactor actuating member to effect rotation thereof and resilient means constantly urging said contactor into engagement with said switch head.

4. A lock switch of the character described, a mounting head provided with a first named bore and adapted to accommodate a mounting cylinder, a second named bore adapted to accommodate a switch mechanism and a third named bore joining said other two bores and of smaller diameter than said first named bore, a lock cylinder mounted in said first named bore for rotation therein and abutting the shoulder formed between said first and said third named bores, a switch head mounted on the outer end of said second named bore, a plurality of switch points mounted on said switch head, a contactor actuating member mounted for rotation within said second named bore, a plurality of arms formed integrally on said

lock cylinder and engageable with said contactor actuating member to effect rotation thereof, a contactor mounted in said contactor actuating member and adapted to 5 selectively engage or disengage said points upon rotation of said actuating member, resilient means constantly urging said contactor into engagement with said switch head and means insulating said last named means 10 from said lock cylinder.

5. In a lock switch of the character described, a mounting head having a first named bore to accommodate a lock cylinder, a second named bore to accommodate a switch 15 mechanism and a third named bore joining said other two bores and of smaller diameter than said first named bore, a lock cylinder mounted within said first named bore and abutting the shoulder formed between said 20 first and said third named bores, a switch head mounted on the outer end of said second named bore, a plurality of switch points mounted on said switch head, a contactor actuating member having an aperture there- 25 through and mounted for rotation within said second named bore, a pair of arms formed on said lock cylinder and engageable with said contactor actuating member to effect 30 rotation thereof, a contactor mounted in said aperture and adapted to selectively engage or disengage said points upon rotation of 35 said actuating member, an insulating member mounted in a recess in said lock cylinder, a spring abutting said insulating member and said contactor to constantly urge said contactor onto said switch head.

6. In a lock switch of the character described, a mounting member having a plurality of axial bores, a lock cylinder mounted 40 in one of said bores for rotary movement between a locked and an unlocked position, a switch head substantially closing another of said bores, a contact on said switch head, a contactor actuating member mounted for 45 rotation within one of said bores, a pair of spaced arms extended from said lock cylinder and engaging said contactor actuating member to effect rotation thereof, and a contactor carried by said actuating member and 50 adapted for engagement with said contact upon rotation of said lock cylinder.

7. In a lock switch of the character described, a mounting member having a plurality of axial bores, a lock cylinder mounted 55 in one of said bores for rotary movement between a locked and an unlocked position, a switch head substantially closing another of said bores, a contact on said switch head, a contactor actuating member mounted for 60 rotation within one of said bores, a pair of spaced arms extended from said lock cylinder and engaging said contactor actuating member to effect rotation thereof, a contactor carried by said actuating member and 65 adapted for engagement with said contact

upon rotation of said lock cylinder, and means constantly urging said contactor away from said cylinder.

In testimony whereof I have hereunto affixed my signature. 70

EDWARD N. JACOBI.
